WRINGER MOP

Harold H. Schwartz, Port Chester, and Jean S. Tucker, White Plains, N. Y., assignors to Empire Brushes, Inc., Port Chester, N. Y., a corporation of New York

Application April 1, 1952, Serial No. 279,814

7 Claims. (Cl. 15—119)

This invention relates to mops.

An object of this invention is to provide a mop comprising a mop head, a block of sponge material attached to the under side of the head, a member hinged to the mop head and swingable towards said block, and a second member hinged to the first hinged member and movable against the block of sponge material so as to facilitate squeezing out water from the block.

Yet another object of this invention is to provide a mop of the character described comprising a mop head, an adaptor removably attached to the under side of said head, a pad of sponge material attached to the under side of said adaptor and extending rearwardly beyond the adaptor, a member hinged at one edge to the head adjacent the adaptor and above said pad, and a second member hinged to the first member about an axis parallel to the first hinged member whereby the first hinged member may swing about its hinge connection to the head and the second hinged member may swing about its hinge connection to the first hinged member for the purpose of thoroughly squeezing water out of the sponge pad.

Yet another object of this invention is to provide in a mop of the character described, an elongated mop handle attached to the head and extending upwardly at an angle thereto, a sleeve slideable on the handle, and means interconnecting the second hinged member with the sleeve for actuating said hinged members.

Still a further object of the present invention is to provide a strong, rugged and durable mop of the character described, which shall be inexpensive to manufacture, easy to manipulate, and which shall yet be practical and efficient to a high degree in use.

Other objects of this invention will in part be obvious, and in part hereinafter pointed out.

The invention accordingly consists in the features of construction, combinations of elements, and arrangement of parts, which will be exemplified in the construction hereinafter described and of which the scope of invention will be indicated in the following claims.

In the accompanying drawings in which is shown various illustrative embodiments of this invention,

Fig. 1 is a perspective view of a mop embodying the invention, with parts broken away and in cross section;

Fig. 2 is a cross sectional view taken on line 2—2 of Fig. 1;

Fig. 3 is a cross sectional view taken on line 3—3 of Fig. 2;

Fig. 4 is a view similar to Fig. 3 but showing the mop pad in squeezed condition;

Fig. 5 is a perspective view of an adaptor and a mop pad removed from the mop head.

Fig. 6 is a cross sectional view taken on line 6—6 of Fig. 2;

Fig. 7 is a cross sectional view taken on line 7—7 of Fig. 2;

Fig. 8 is a cross sectional view taken on line 8—8 of Fig. 2;

2

Fig. 9 is a bottom plan view of a head member to which the handle is attached, and

Fig. 10 is a cross sectional view taken on line 10—10 of Fig. 6.

Referring now in detail to the drawing, 10 designates a mop embodying the invention. Said mop comprises a head 11, a handle 12 attached to said head and a mop element 13 detachably attached to the head.

The head 11 comprises a member 14 which may be made of rigid synthetic plastic material preferably as a molding. Said member 14 comprises a front wall 15 having a downwardly projecting front flange 16. The flange 16 has a lower edge 17 and a rear inner surface 18 extending upwardly from the lower edge. At the upper end of the inner surface 18 is a rearwardly extending under surface 19 forming a shoulder. Extending upwardly from the rear end of the surface 19, the front wall 15 is formed with an inner vertical surface 20.

Extending rearwardly from the upper end of the front wall 15 is a top wall 21 from the ends of which extend downwardly a pair of diverging side walls 22. Said side walls also extend to the front wall 15. The side walls 22 have lower edges 23 and rear edges 24. The rear ends of the side walls 22 extend somewhat beyond the rear edge 25 of the top wall 21. Said side walls 22 may be somewhat longitudinally curved as shown in Fig. 9 of the drawing, if desired.

The top wall 21 is formed with a central raised portion 26. Said raised wall 26 is formed with a central opening 27. Said raised wall 26 has a rear end edge 28 and inner side walls 29 extending downwardly. Said side walls are interconnected by a horizontal shelf 30 spaced below the under surface 31 of the raised wall 26. The shelf 30 has a rear edge 31 in alignment with the rear edge 25 of the top wall 21 and a front edge 33. The rear end of the top surface of the shelf 30 merges with the rear end of the top surface of the wall 21. Between the shelf 30 and the underside of the raised wall 26 is formed a horizontal slot 34, for the purpose hereinafter appearing.

Extending downwardly from the under side of the top wall 21 on opposite sides of the raised wall 26 are a pair of integral ears 36 formed with aligned through openings 37. The ears 36 are located substantially midway between the front wall 15 and the rear edge 25. The side walls 22 are formed with integral inwardly extending bosses 38 formed with through openings 39 aligned with the through openings 37.

Extending through the aligned openings 37, 39 is an elongated hinge pin 40. The hinge pin 40 is located below the level of the shaft 30 as shown in Fig. 3 of the drawing. Pivoted to the hinge pin 40 is a first hinged member 41 likewise preferably made of rigid, synthetic, plastic material. The member 41 is formed at its front end with forwardly extending ears 42 substantially contacting the bosses 38 and formed with through openings 43 registering and aligned with the openings 39.

Said member 41 is also formed with forwardly extending ears 44 substantially contacting the outer sides of ears 36 and formed with through openings 45 registering and aligned with the through openings 37. The hinge pin 40 passes through openings 43 and 45 of the ears 42 and 44 thereby hinging member 41 to said hinge pin. Member 41 is located between the side walls 22 and has end edges 47 spaced inwardly of said side walls, the ears 42 and 44 of member 41 project downwardly from said member as shown in Fig. 6 of the drawing.

Said member 41 is furthermore formed with rearwardly extending ears 50 aligned with the ears 44 and formed with aligned through openings 51. Said member 51 is also formed with rearwardly extending ears 52 formed with through openings 53 aligned with through openings

51. The ears 52 are located inwardly of the ears 42 as shown in Fig. 2 of the drawing. Extending through the aligned openings 51, 53 in the ears 52 is a horizontal elongated hinge pin 54 parallel to the hinge pin 40. The outer ends of the pin 54 extend beyond the ears 50, for the purpose hereinafter appearing. It will be noted that the ears 50, 52 are located substantially at the rear ends of the side walls 22.

Hinged to the hinged pin 54 is a second hinged member 55 likewise preferably made of rigid, synthetic, plastic material. Said member 55 has forwardly extending ears 56 substantially contacting the outer side of ears 52 and formed with through openings 57 aligned with openings 53 and receiving the outer ends of the hinge pin 54. Said hinge member 55 is furthermore formed with a pair of ears 57 substantially contacting the inner sides of the ears 50 and formed with through openings 58 aligned and registering with the through openings 51 and through which the hinge pin 54 passes.

Said member 55 is formed with notches 60 into which the ears 50, 52 project. Said member 55 may furthermore be formed with a plurality of parallel slots 61 disposed transversely of said member and perpendicularly of the rear edge 62 of said member. Said rear edge 62 may be formed with an upwardly extending, reinforcing lip 63, if desired. The slots 61 are in two sets or series of slots disposed on opposite sides of the mid portion of member 55, as shown in Figs. 2 and 10 of the drawing. Said member 55 may be furthermore slightly transversely curved, as shown in Fig. 3.

Said member 55 is formed at its upper side with two aligned pairs of spaced, upwardly extending apertured ears 64 and 65 located between two sets of slots 61. The ears 64 carry a transverse rivet 66 whereas the ears 65 carry a transverse rivet 67. Pivoted to the rivets 66 and 67 and having their lower ends received in the slots between the ears 64 and 65 are links 68 and 69 interpivoted at their upper ends by a common rivet 70. The link 68 has an offset lug 71, for the purpose hereinafter appearing.

The handle 12 may be made of tubular metal. Its lower end is flattened as at 75 and offset to an angle of about 45° to the handle. Said flattened together portion 75 is formed with a through opening 76. The flattened portion 75 is inserted through the slot 34 and against the under surface 31 of the raised top wall portion 26 and against the rear surface of the front wall 15. In such position, the opening 76 will register or be centralized with the opening 27 in said raised wall 26. It will now be understood that the first swinging member 41 is swingable downwardly relative to the member 14, and that member 55 may be swung relative to members 41 and 14. Thus, members 41, 55 may be moved from the position shown in Fig. 3 to the position shown in Fig. 4.

To effectuate this swinging movement, there is slidably mounted on the handle 12, a sleeve 80 having a lower flaring mouth 81. Pivoted to the bottom of the mouth 81 as by a rivet 82 is a connector piece 83. Interconnecting the rivet 70 at the upper end of the links 68, 69 with a rivet 84 at the lower end of the connecting member 83, is a connecting rod 85. It will be noted that the rivets 84 and 70 are parallel to one another but the rivet 82 is perpendicular to the rivet 84. Thus, the connector 83 has its upper end twisted to 90° of its lower end, as shown in the drawing.

The mop element 13 is mounted at the under side of the head member 14. Said mop element 13 comprises an adaptor 86 which may be made of wood, plastic or other rigid material. The member 86 is elongated and of angular cross section and comprises an upwardly extending flange 87 and a forwardly extending flange 88. The flange 88 contacts the surfaces 18 and 19 of the member 14 whereas the flange 87 contacts the rear surface of the front wall 15.

Extending through the center of the vertical flange 87

is a vertical screw 90 having a shank 91 projecting above the adaptor and passing through the openings 76 and 27 and thereabove. Said screw has a head at its lower end received in a countersunk opening in the adaptor. A nut 92 is screwed to the projecting end of the screw for tightly pressing the adaptor against the member 14.

Glued or otherwise adhered to the under side of the adaptor is a block or pad 95 of sponge-like material such as synthetic sponge. The block or pad 95 has a front surface 96 registering with the front edge of the flange 88. Said pad 95 extends rearwardly of the adaptor 86. The side walls 22 of the member 14 are formed with grooves 97 at the lower ends straddling the block or pad 95. Said pad preferably extends beyond said opposite side walls 22.

It will now be understood that the mop element 13 may be removed by unscrewing the nut 92. Mopping is done with the parts in the position shown in Figs. 1 and 3. In such position, the sleeve 80 is up. The hinged element 41 is held against the under side of the shelf 30 by means of a pair of torsion springs 100 on the pivot pin 40 and disposed between the pairs of ears 42, 44.

The member 55 is maintained in the raised position of Figs. 1 and 3 by a pair of torsion springs 101 on the pin 54 and located between the pairs of ears 50, 52. In such position, the lug or projection 71 on the link 68 contacts the handle 12. Thus, the shelf 30 limits the upward movement of the hinged member 41 whereas the lug 71 limits the upward movement of member 75. Member 41 is located above the rear end of the pad, whereas member 55 is located back of the pad.

To squeeze the water out of the mop block or pad 95, it is merely necessary to push the sleeve 80 downwardly on the handle 12, thereby causing member 55 to be swung downwardly in a clockwise direction about the hinge pin 54. At the same time, the member 41 is swung downwardly about the pin 40, thereby causing the lowering of the hinge pin 54. Such movement will cause the hinge member 55 to press against the pad 95 and to squeeze it upwardly so as to cause thorough compression of the pad for effectively squeezing water out of the pad. After the squeezing operation, the sleeve 80 is released, and the torsion springs 100, 101 will restore the members 41 and 55 to normal raised position. During the squeezing operation, water will squeeze through the slots 61.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

We claim:

1. A mop comprising a mop head member having a front wall, a top wall extending rearwardly from the front wall and side walls interconnecting said front wall and top wall, a handle having a lower end portion positioned against the top wall, a mop element comprising a mounting adaptor, means attaching the adaptor and the handle to said mop head member, a mop pad of sponge material attached to the under side of the adaptor and projecting below said mop head member, a first hinged member hinged to the mop head member and disposed below said top wall and between said side walls and above a portion of the pad, a second hinged member hinged to the first hinged member and extending rearwardly beyond said mop head member, and means including a member slidably on the handle and a link operatively connected to said second hinged member for causing swinging movement of said first hinged member relative to the mop head member and swinging movement of the second hinged member relative to the first hinged

member to move both hinged members into contact with the pad to squeeze the latter.

2. The combination of claim 1 in combination with torsion spring means to raise the first hinged member relative to the mop head member and to raise the second hinged member relative to the first hinged member.

3. The combination of claim 2 in combination with means to limit the upward movement of the first hinged member relative to the mop head member and means to limit the upward swinging movement of the second hinged member relative to the first hinged member.

4. A mop comprising a mop head having a front wall, a top wall and depending side walls, a handle extending upwardly from the rear of the mop head, a relatively narrow mounting adaptor mounted on the underside of the head at the front portion thereof, a mop pad of sponge material carried by the underside of the adaptor and projecting below the lower edges of the side walls of the head, the rear portion of the pad extending rearwardly beyond the rear portion of the adaptor, a first hinged member hinged at its forward edge between the side walls of the head directly behind the adaptor and disposed above the exposed rear portion of the pad and mounted for swinging movement between said side walls, a second hinged member hinged at its forward edge 25 to the rear edge of the first hinged member, means for normally holding the hinged members in a raised non-squeezing position, and means for swinging the first hinged member downwardly and forwardly and for swinging the second hinged member downwardly, forwardly 30 and then upwardly to move both hinged members into

contact with the rear portion of the pad to squeeze the latter against the front wall of the head and against the adaptor.

5. The structure defined in claim 4, wherein the means for swinging the hinged members includes a sleeve slideable on the handle, and a lever and link assembly connecting the slideable sleeve with the second hinged member.

6. The structure defined in claim 5, including stops for limiting the upward swinging movement of the respective hinged members.

7. The structure defined in claim 4, wherein the second hinged member is formed with a series of openings to permit the water to pass therethrough when the second hinged member is in a pad-squeezing position.
